UNITED STATES PATENT OFFICE.

THOMAS H. FURMAN, OF SEWARD, DISTRICT OF ALASKA.

INDEPENDENT ATTACHMENT FOR LAMP-CHIMNEYS, &c.

No. 839,283.

Specification of Letters Patent.

Patented Dec. 25, 1906.

Application filed June 19, 1906. Serial No. 322,367.

To all whom it may concern:

Be it known that I, THOMAS H. FURMAN, a citizen of the United States, residing at Seward, in the District of Alaska, have invented new and useful Improvements in Independent Attachments for Lamp-Chimneys and the Like, of which the following is a specification.

This invention relates to devices used as independent attachments to lamp-chimneys and other like devices to form a rest or support for heating different bodies or vessels by the flame or heat of the lamp or of gas and also for heating hair curling and crimping irons or for any other purpose.

The primary object of the present improvement is to provide a support having a convenient structure to adapt it for use either as a means for holding a cup or similar vessel on the top of a lamp or gas shade and also to provide in the same device means for holding and guiding a curling or crimping iron or implement, whereby one device may be used for different purposes at a minimum cost of manufacture and without materially increasing the structural features of rests or supports of this class as ordinarily constructed.

The invention consists in the construction and arrangement of the several parts, which will be more fully hereinafter set forth.

In the drawings, Figure 1 is an elevation of a portion of a chimney, showing the improved attachment applied thereto in edge elevation and as holding a hair-crimping iron. Fig. 2 is a top plan view of the improved device or attachment. Fig. 3 is a bottom plan view thereof.

Similar numerals of reference refer to like parts throughout the several views.

The numeral 1 designates a disk-like body having such diameter as to fit over the upper end of a lamp-chimney or over a gas-shade and provided with a central opening 2 and a handle 3. Rising from the upper surface of the body 1 are radial ribs 4, which connect with a central circular boss 5, surrounding the opening 2, the upper surfaces of the boss and ribs being flush. The ribs at their outer extremities are formed with vertical projections 6, and the inner portion of the boss 5 has notches 7 therein communicating with the central opening 2, the object of these pro-

jections and notches being to permit the air to freely pass inwardly and outwardly over the body 1 when a cup or other similar vessel is placed on the attachment for the purposes of heating water or other liquids, and thus obviating any tendency of causing the lamp to smoke or interfering with combustion and the illuminating properties of the lamp or gas. The opening 2 is adapted to removably receive a hair-curling iron 8, as shown by Fig. 1, the boss 5 adding sufficient thickness to the body 1 to provide a positive guide and support for the iron 8.

The under or bottom side of the body 1 is formed with a series of radial flanges 9, having their outer end edges inwardly beveled, as at 10, to adapt the device to be inserted in the upper end of a lamp-shade. The lower free edges of the flanges 9 also have projections 11 at their outer terminals, which may serve as feet or supports for the attachment when it is removed from the lamp and disposed upon some cooling means, and thus permit the air to freely circulate under the flanges. The under side of the body 1 also has an angular guard 12 thereon in line with the handle 3 to shield and render the latter cool, or, in other words, to reduce the heated condition of the handle as much as possible, so that it may be readily grasped.

It is proposed to construct the improved attachment of any suitable metal adapted for the purpose and may be either sheet form or cast. It is also proposed to avoid the use of solder or forming joints that might become separated owing to the intense heat to which the attachment is subjected when in use.

The improved attachment will be found exceptionally convenient, and it will be understood that it will be made in various sizes. By having the flanges 9 formed with outer beveled edges 10, as set forth, the body 1 is adapted to fit the upper ends of chimneys or shades of different diameters, said flanges forming vents between the said body and the upper edge of the chimney for the escape of the products of combustion from the interior of the chimney.

What I claim is—

An attachment of the class set forth comprising a body having an opening through the center thereof surrounded by a boss with

vent-notches in the inner edge of the same, and radial ribs extending from the said boss and terminating in projections which extend above the upper edges of said ribs, all arranged 5 on one side of said body, the opposite side of the body being provided with radial flanges around the central opening and an angular guard, the body adjacent to the guard hav-

ing a handle projecting outwardly therefrom which is shielded by said guard.

In testimony whereof I affix my signature in presence of two witnesses.

THOMAS H. FURMAN.
